UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

PRESSING ELEMENT FOR LAUNDRY AND GARMENT PRESSING MACHINES

Application filed February 15, 1929, Serial No. 340,139. Renewed October 8, 1930.

This invention relates to platen pressing elements as heads or bucks of garment and laundry pressing machines, particularly heads or bucks of light weight construction consisting of a light main plate and light sheet metal plates which form the heating chamber of the element, and has for its object a particularly simple, efficient and economical construction by which the conduit, from which a fluid, as steam or air, or both, is projected through the pressing face, is secured to the main plate of the head or buck, or assembled in the head or buck construction.

15 The invention consists in the novel features and in the combinations and constructions hereinafter set forth and claimed.

In describing this invention reference is had to the accompanying drawings in which like characters designate corresponding parts in all the views.

Figure 1 is a plan view of a press head embodying this invention.

Figures 2 and 3 are respectively a central longitudinal and transverse sectional views taken of Figure 1, the latter being on an enlarged scale.

Figure 4 is a perspective view, partly broken away.

30 Figure 5 is an enlarged fragmentary cross sectional view through the steam conduit and contiguous parts.

Figure 6 is a fragmentary side elevation of a pressing machine embodying this pressing element.

This pressing element comprises a rigid main plate having a lengthwise slot, a conduit for a fluid, as steam or air, having a lengthwise rib fitting the slot and formed 40 with jet openings through which a fluid as steam or air may be projected from the conduit to the pressing face, a sheet metal plate overlying and secured to the main plate and shaped to form a chamber for a heating medium, as steam, and a valve controlled conduit through which steam or air is supplied to the former conduit.

45 1 designates the main or body plate, this being formed rigid. It may be a casting or sheet metal.

2 designates the lengthwise slot formed therein and opening through its upper and lower faces.

3 is the conduit for a fluid, usually steam, for steaming the garment, although air may be used to dry the garment. The conduit 3 has a lengthwise rib portion 4 fitting the slot 2 and formed with shoulders 5 at the base of the rib overlying or thrusting against the margin of the plate 1 along the slot 2 (Figure 2). It also has additional shoulders 6 under which extend the margins of a slot formed in the sheet metal plate to be presently described.

65 The rib portion 4 is formed with perforations or jet openings 7 therethrough leading from the interior of the conduit to the pressing face of the plate 1.

8 is a crowned sheet metal plate overlying the plate 1 and secured at its margins 9 thereto as by welding, the plate 8 confining a chamber for a heating medium as steam. The plate is formed with an inlet 10 and an outlet 11 for the steam.

70 The plate 8 is formed with a number of internal corrugations 12, the crowns 13 of which are secured as by welding to the plate 1. The corrugations terminate short of the ends of the crowned portion, Figure 1, so that the steam can be distributed through 75 the crown portions 13 around the ends of the corrugations.

80 The conduit 3 is located in the intermediate corrugation and the rib portion extends through a slot in the crown of the intermediate corrugation aligned with the slot 2. The margins of the crown along the slot extend at 14 under the shoulder 6. The open upper side of the intermediate corrugation is closed by a cover plate 15 secured at its margins 16 as by welding. The corrugation beneath the cover plate is preferably packed with a heat 85 distributing material as copper wool.

17 is a conduit communicating with the steam chamber formed by the plate 8 and with the conduit 3, the conduit 17 being connected to a valve casing 18 mounted on a portion 19 of the conduit 3, which portion extends through the cover plate 15. The portion 19 is formed with an inlet passage 20. 100

The movable valve member in the casing 18 is operated by a hand lever 21.

22 is a carrier plate to which the yoke lever 23, Figure 6, of the pressing machine is secured, the carrier plate being slidably mounted on studs 24 projecting from blocks 25 secured, as by welding in depressions or corrugations in the plate 8. Compression springs 26 are interposed between the carrier plate 22 and the blocks 25 to yield when the head goes under heavy pressure on the buck 27 of the pressing machine.

The head or the yoke lever is actuated by any suitable mechanism.

15 The pressing element is light, strong, and economical in construction, and the steam conduit 3 is applied thereto in a particularly simple and economical manner.

What I claim is:

20 1. A pressing element for pressing machines comprising a plate having a pressing face and a lengthwise slot opening through its opposite faces, a conduit mounted on the plate and having a lengthwise rib portion fitting the slot and formed with jet openings through which a fluid may be discharged from the conduit to the pressing face.

25 2. A pressing element for pressing machines comprising a plate having a pressing face and a lengthwise slot opening through its opposite faces, a conduit mounted on the plate and having a lengthwise rib portion fitting the slot and formed with jet openings through which a fluid may be discharged from the conduit to the pressing face, a sheet metal crowned plate secured at its margins to the first plate and formed with internal corrugations, the crowns of which are secured to the first plate, the corrugations terminating short 30 of the ends of the crowned plate, one of said corrugations having a slot alined with the slot in the first plate and the rib portion of the conduit extending through said slot.

35 3. A pressing element for pressing ma-

40 chines comprising a plate having a pressing face and a lengthwise slot opening through its opposite faces, a conduit mounted on the plate and having a lengthwise rib portion fitting the slot and formed with jet openings through which a fluid may be discharged from the conduit to the pressing face, a sheet metal crowned plate secured at its margins to the first plate and formed with internal corrugations, the crowns of which

45 are secured to the first plate, the corrugations terminating short of the ends of the crowned plate, one of said corrugations having a slot alined with the slot in the first plate and the rib portion of the conduit extending through said slot, and a cover plate for the open side of the corrugation in which said conduit is located.

50 4. A pressing element for pressing machines comprising a plate having a pressing face and a lengthwise slot opening through

its opposite faces, a conduit mounted on the plate and having a lengthwise rib portion fitting the slot and formed with jet openings through which a fluid may be discharged from the conduit to the pressing face, a sheet metal crowned plate secured at its margins to the first plate and formed with internal corrugations, the crowns of which are secured to the first plate, the corrugations terminating short of the ends of the crowned plate, one of said corrugations having a slot alined with the slot in the first plate and the rib portion of the conduit extending through said slot, a cover plate for the open side of the corrugation in which said conduit is located, and a packing material in said corrugation around the conduit.

55 5. A pressing element for pressing machines comprising a plate having a pressing face and a lengthwise slot opening through its opposite faces, a conduit mounted on the plate and having a lengthwise rib portion fitting the slot and formed with jet openings through which a fluid may be discharged from the conduit to the pressing face, a sheet metal crowned plate secured at its margins to the first plate and formed with internal corrugations, the crowns of which are secured to the first plate, the corrugations terminating short of the ends of the crowned plate, one of said corrugations having a slot alined with the slot in the first plate and the rib portion of the conduit extending through said slot, a cover plate for the open side of the corrugation in which said conduit is located, the conduit having a portion extending through the cover and formed with an inlet for a fluid and a control valve mounted on said portion of the conduit.

In testimony whereof, I have hereunto signed my name, at Syracuse, in the county of Onondaga and State of New York, this 13th day of Feb., 1929.

ERNEST DAVIS.
